UNITED STATES PATENT OFFICE

GEORGE H. STEVENSON, OF NEW YORK, N. Y., ASSIGNOR TO WESTERN ELECTRIC COMPANY, INCORPORATED, OF NEW YORK, N. Y., A CORPORATION OF NEW YORK

BUSHING FOR HIGH FREQUENCY HIGH VOLTAGE CURRENT

Application filed September 1, 1925. Serial No. 53,774.

This invention relates to electric insulators of the bushing type and specifically to an insulator which is particularly well adapted for use in high frequency and high voltage current systems such as radio broadcasting systems and the like.

In ordinary high potential electric systems the failure of an insulator is generally due to flash-over, or to fracture of the insulating material by the disruptive discharge of a high voltage surge, such as may be caused by lightning, or by some sudden change in the circuit conditions. The insulation of high frequency voltages, for example those occurring in a radio transmission system, is made more difficult by the presence of an additional cause of failure, namely the heat generated in the insulating material by the high frequency alternations of electric stress. It has been found in practice that this is the most important cause of the failure of insulators at high frequencies, the heat generated being sufficient to soften the plastic dielectrics or to fracture the vitreous or ceramic dielectrics of insulators of the common types.

An object of the invention is to reduce to a minimum the effect of high frequency energy dissipation in the dielectric of an insulating bushing.

30 A further object is to prevent damage to the dielectric of an insulating bushing due to flash-over.

The invention accomplishes the objects broadly by the application of the following rules: First, the insulating material and the surfaces of the metallic conductors should be in such geometrical form that the dissipation of energy in the form of heat is approximately uniform at all point in the dielectric.

40 This implies that all points of the dielectric are subject to the same electric stress and requires that the metallic surfaces be carefully disposed so that a region of uniform potential gradient is produced between the conductors at different potentials. It also requires that the dielectric be placed in this region of uniform gradient in such manner that it does not by its presence distort the electric field. In other words the surfaces of

the dielectric must be parallel to the lines of electric force between the conductors.

Second, the material of the dielectric should be so disposed that the heat generated at internal points is readily conducted to the surface where it may be radiated to the surrounding air. The material should be thin and of large surface area in order that this may be best accomplished.

Third, to prevent injury to the dielectric by flash-over a safety gap should be provided so that flash-over due to a sudden excess voltage may take place in air as far away as possible from the insulating material.

In accordance with this invention a bushing is provided comprising a central conducting rod having end discs of conducting material connected thereto, a torus of conducting material encircling said rod and being held in spaced relation thereto by cylindrical tubes of insulating material connected to one end to the torus and at the other end to the respective end discs, and a support to which the torus is attached for mounting the bushing, the torus preferably having a flange for this purpose, the torus in conjunction with the end discs and central conducting rod constituting a system of conductors to establish a uniform electric field throughout the insulator, and to provide a discharge gap in air for excess voltages.

Other features of the invention and advantages will appear from the following description and by the claim appended thereto, reference being had to the accompanying drawings in which:

Fig. 1 is an assembly view of the bushing partially in section, and

Fig. 2 an end view thereof also partially shown in section.

The bushing made according to this invention generally consists of a lead-in rod 10 on the ends of which the metal discs 11 and 12 are mounted. These discs are held in spaced relation with respect to a centrally disposed metal torus 13 by means of two cylindrical members 14 and 15 which are made of a material having low dielectric

hysteresis such as pyrex or high grade phenol fibre.

The metal torus has a flange or fin portion 16 adapted for securing the bushing to the panel or casing from which the conductor 10 is insulated.

Each disc 11 and 12 is provided with a recessed portion as shown at 17 which serves to hold the associated cylindrical insulators 18 in their proper positions. Rings 21, of soft material such as lead may be provided to act as gaskets between the ends of insulating cylinders and the discs.

Similarly, the metal torus 13 is provided with two oppositely disposed recesses in which the rings 19 and 20 of soft material are also inserted. The component parts of the bushing are clamped together by means of nuts threading on the ends of the lead-in rod 10. The threaded ends of conductor 10 serve also as means for connecting the external conductors 22 and 23 to the bushing.

The lines of force of the electric field are indicated by the dotted lines in Figure 1. The principal elements determining their contour in the neighborhood of the insulating cylinders are the end discs and the central panel or casing. If these constituted a system of three infinitely extended parallel plates, the two discs being at one potential and the panel at a different potential, the electric field would be uniform at all points and the lines of force would be of uniform density and parallel.

On account of the limited dimensions of the discs and of the necessity of having a hole in the panel for the lead-in conductor the field is distorted, but to a large extent this distortion is overcome in the neighborhood of the insulators by the relatively large curvature of the torus 13 and by the provision of a substantial overlap of the end discs as indicated at 18.

At the same time the combination of the torus 13 and the rod 10 passing through the center forms a safety gap which has a very definite discharge voltage, particularly if the rod 10 is of substantial diameter. The rod 10 and the torus 13 should preferably have thicknesses of the same order of magnitude and the inner diameter of the torus should be about twice or three times the diameter of rod 10. In addition the length of the cylindrical insulators 14 and 15 should preferably not exceed their diameter. In the design of an insulator for a specific purpose the basic dimension is the sparking distance between the torus and the rod. When this is established to provide a proper margin of safety under operating conditions the other dimensions are readily determined with a sufficient degree of accuracy by the simple rules given above.

What is claimed is:

65 An insulating bushing for high frequency

high voltage currents comprising a metal rod, metal discs mounted on the ends of said rod and each having a groove in its inner face, a ring of soft material in each groove, a flanged metal torus encircling said rod and having in each face a groove at the junction of the flange and tubular portion of the torus, a ring of soft material in each groove, means for securing the flanged portion of the torus to a casing wall, a pair of straight integral cylinders of insulating material thin enough to maintain such material at a substantially uniform temperature throughout its cross section when subjected to high frequency high voltage currents, each cylinder 80 engaging at one end a ring in a disc and at its other end a ring in said torus, the curvature of the torus being relatively large and the discs having a substantial overlap beyond the cylinders.

In witness whereof, I hereunto subscribe my name this 24th day of August, A. D. 1925.

GEORGE H. STEVENSON.
